(57) **CLAIM**

The ornamental design for a connector as shown and described.

DESCRIPTION

FIG. 1 is a front elevational view of a connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof. The dashed broken line showing of the connector is for the purpose of illustrating portions of the article, and the dot-dash broken line defines the bounds of the claimed design. The dashed broken line and the dot-dash broken line form no part of the claimed design.
